UNITED STATES PATENT OFFICE.

HERMAN A. DAVENPORT, OF BROCKTON, MASSACHUSETTS, ASSIGNOR TO UNITED SHOE MACHINERY CORPORATION, OF PATERSON, NEW JERSEY; A CORPORATION OF NEW JERSEY.

LEVELING MACHINE.

Application filed May 26, 1923. Serial No. 641,697.

This invention relates to machines for pressing shoes and is illustratively disclosed in connection with a leveling machine of the so-called automatic type in which a leveling tool and a shoe carrying jack are automatically relatively reciprocated to cause the tool to operate over the shoe bottom.

In machines of the above-mentioned type the shoe is supported bottom upward on a jack comprising a heel pin for engaging the last in its spindle hole, and in the relative movements of the leveling tool or roll and the jack lengthwise of the shoe roll is tipped at times so that it operates along the side edges of the sole with its axis at a substantial inclination to the height of the shoe, thus applying pressure directed laterally of the shoe. The tendency, therefore, is for the roll, as it operates along the opposite side edges of the sole under the heavy spring pressure necessary for shaping the sole in a satisfactory manner, to swing the shoe about the heel pin, first in one direction and then in the opposite direction.

To assist in supporting the shoe against this lateral pressure and against downward pressure, leveling machines are commonly provided with a toe rest hollowed out to receive the toe end of the shoe and faced with leather. Considerations of economy, both in respect to machine equipment and in respect to the operator's time, have not rendered it practicable to provide and to utilize for every size and style of shoe a toe rest exactly fitted to the shape of the toe of that shoe. Under most conditions, therefore, there is opportunity for the toe to slip to some extent on the toe rest under the lateral pressure of the leveling tool; nor is this tendency entirely overcome even where the toe rest is shaped to conform closely to the contour of the toe. This tendency of the toe to slip on the toe rest has often resulted in damage to shoes by reason of the rubbing action of the rest on the surface of the upper leather.

While, therefore, the object has been heretofore to prevent, as far as practicable, any lateral movement of the shoe in the leveling operation, there are other objectionable results that are due in large measure to the absence of provision for substantial relative movement of the shoe and the leveling tool

laterally of the shoe. As leveling machines are constructed, the support for the leveling roll permits the roll to move or yield bodily, in accordance with variations in the contour of the bottom of the shoe, only in directions heightwise of the shoe. Such movement of the roll, when the roll is inclined or tipped as above described, results not only from variations in the contour or slope of the bottom face of the sole, but also from variations in the width of the sole on different portions of the shoe. It will thus be evident that in passing, for example, from the shank to the ball of the shoe the inclined roll is lifted, both because the ball of the inverted shoe is higher than the shank and also because the ball is wider than the shank. Such movement of the roll in a direction inclined to its axis, whether it moves upwardly or downwardly in accordance with variations in the contour of the shoe, causes the roll to rub more or less on the margin of the sole. In operating along the side edges of the sole the roll thus has at times a combined rolling and rubbing action, and this frequently results in an intermittent jumping of the roll from one point to another which produces along the edge of the tempered sole an objectionable wrinkled or wavy condition.

It will be readily understood that this rubbing action of the inclined roll on the margin of the sole in its upward or downward movement, in so far as such action occurs, is due to the fact that there is no provision for substantial compensating movement of either the shoe or the roll in directions laterally of the shoe. While it is true, as above stated, that the toe rest as heretofore constructed frequently permits some lateral displacement of the toe of the shoe, this displacement is not enough to alleviate substantially the objectionable rubbing of the roll on any portion of the margin of the sole. Furthermore, such displacement of the toe on a leather toe rest is likely to occur all at once, and thereafter in the continued action of the roll along the edge of the sole the shoe is supported against further lateral yield and there is consequently nothing then to prevent further rubbing of the roll on the shoe. Moreover, after the shoe has been pushed over, for example, by the action of the roll on

the wide ball portion of the sole, it remains in that position, and when the roll then passes to the narrower part of the sole near the toe, it does not apply the pressure that it would if the toe were central. Similarly, when the roll tips to the other side of the sole, it begins to act on that side with the toe in an abnormal position, until it suddenly effects a displacement of the shoe in the opposite direction to the limit permitted by the toe rest. It will thus be seen that provision merely for lateral displacement of the shoe in response to pressure, as by slipping of the toe on a toe rest, does not afford any material improvement in the conditions under consideration since there is nothing which acts to return the shoe or to centralize it. Lateral movement of the shoe in one direction can compensate only for vertical movement of the inclined roll in one direction, for example when the roll moves upward, and in order properly to counteract the tendency for the roll to rub on the sole when it moves downward, a lateral movement of the shoe in the opposite direction is required. Even, therefore, if toe rests as heretofore constructed afforded provision for substantial lateral movement of the shoe, conditions affecting the action of the roll on the edge of the sole would not be materially improved, and in some respects would be still more detrimental to good work.

The present invention accomplishes a very important improvement in leveling machines by provision for substantial relative movement of the leveling tool and the shoe laterally of the shoe under conditions that insure the proper action of the tool on the different portions of the shoe. In one important aspect, the invention provides for relative movement of the tool and the shoe laterally of the shoe in different directions at different times in the progressive action of the tool along the side of the shoe, thus avoiding objectionable rubbing of the margin of the sole where pronounced variations in the contour of the sole are encountered by the tool, and at the same time maintaining such a relation between the tool and the shoe as to insure proper leveling pressures on the different portions of the margin of the sole. In the construction herein shown as an illustrative embodiment of the invention provision is made for relative yield of the shoe and the tool laterally of the shoe, in response to such increase of pressure as results, for example, when the tool encounters the wider and higher portions of the sole, under control of resilient means which acts, as permitted, to effect relative return movement of the shoe and the tool. For the purposes in view the machine herein shown comprises

in its organization a leveling roll which is yieldable heightwise of the shoe, and a shoe support having shoe positioning and controlling means which is resiliently yieldable laterally of the shoe. More particularly, in the illustrative machine provision for such lateral yield of the shoe is afforded by the use of a toe supporting cushion or rest of soft rubber of such thickness as to be deformed or distorted to a substantial extent in response to the pressure of the leveling tool laterally of the shoe. While permitting sufficient displacement of the shoe to avoid objectionable consequences such as heretofore encountered due to the slipping of the roll on portions of the margin of the sole, for example in passing from the shank to the ball of the shoe, this toe rest also tends constantly to return the toe to a central position. This not only insures that the shoe will be properly centralized as the roll tips from one side of the sole to the other, but also serves to prevent the roll from rubbing on the sole as narrower portions of the sole are presented to it, while at the same time insuring a proper degree of pressure on the narrower parts of the sole as well as on the wider parts. A still further advantage in the use of this toe rest is that when the roll is horizontal it permits the shoe to be depressed somewhat as the roll acts on the high portions of the sole, and presses the shoe up toward the roll as the latter passes to the lower portions, thus contributing to an even rolling action.

A further very important object accomplished by the present invention is the elimination of objectionable results heretofore encountered due to the rubbing of the toe of the shoe on the toe rest. The soft rubber toe rest clings to the surface of the upper, even when the shoe is displaced laterally to a very considerable extent. In other words that portion of the rubber which is in contact with the shoe moves with the shoe, and there is thus no danger of damaging the surface of the upper.

These and other features of the invention comprising certain combinations and arrangements of parts will be understood from the following description of a preferred embodiment thereof selected for purposes of illustration and shown in the accompanying drawings, in which,

Fig. 1 is a fragmentary side elevation of the machine;

Fig. 2 is an enlarged perspective detail; and

Figs. 3 and 4 show modifications of the toe rest.

The illustrated machine is also shown and described in the joint application of E. E. Winkley and myself, Serial No. 642,

678 filed May 31, 1923, to which reference may be made for a fuller description of features not herein fully described.

The main frame 10 of the machine has 5 the leveling arms 12 pivoted in trunnions in its upper rear portion as shown at 14. These leveling arms are tubular and contain shafts 16 which at their forward ends carry the heads 18 in which the leveling 10 rolls 20 are pivotally mounted. These shafts are rockable by mechanism not necessary to be described here as it is not a part of the present invention. Reference may be made to the application above mentioned for a 15 description of it, or to the patent No. 889-287, issued June 2, 1908, on the application of E. E. Winkley, which shows a similar mechanism. Its operation may be briefly described by saying that a main cam produces a standard tipping cycle, and other 20 adjustable cams modify this tipping cycle according to their settings by the operator.

The shoe 54 is held on a jack comprising a heel post 56 and a toe post 58 pivoted 25 together at 60 to permit adjustment to accommodate different lengths of shoes and mounted on a shaft 62 which is rocked by a link and lever mechanism operated by a main cam 64 and a pair of auxiliary cams 30 not shown. The jack (of which there are two) and its operating mechanism will be found fully described in the Patents Nos. 1,011,301, issued Dec. 12, 1911 on the application of E. E. Winkley, and 1,239,664, 35 issued Sept. 11, 1917 on the application of W. C. Baxter, and need not be further described here.

The leveling rolls are resiliently forced down upon the shoe by the pressure of 40 springs 68 mounted in vertical channels in the main frame. These springs press at their bottom ends upon levers 70 pivoted at their rear ends on the main frame at 72 and at their front ends to vertically extending links 74 which are pivoted to the leveling arms 12. The upper ends of the 45 springs are engaged by plungers 76 provided with lugs 82 with which the arms 84 on the rock-shaft 86, which is mounted 50 on the frame, are in engagement.

The rock-shaft 86 is operated by a link 90 pivoted to an arm 91 on the shaft and to the end of a lever 92 upon which is adjustably mounted the end of a link 94 having a roll 96 contacting with a cam 98 mounted on the main shaft 25. The lower arm of the link 94 has a slotted bearing on the main shaft to hold it in position. The high points upon the cam 98 raise the link 94 and exert pressure through the spring 68 upon the leveling arms and the low places on the cam are designed to relieve this pressure to a desired extent in certain parts of the shoe or to remove it entirely as 65 may be desired. The cam 98 revolves

once during a leveling cycle and its high and low points determine the pressures applied at different points on the shoe and at different times during this cycle.

In the present machine the cam 98 is 70 constructed to relieve the impressed mechanical pressure entirely at the instant that the roll is passing over the toe tip at the beginning and end of the leveling operation. The weight of the leveling arms 12 75 at these times is carried by upwardly spring pressed plungers 100 arranged to carry this load, but not substantially more. As soon as the strong springs 68 come into action, the effect of the plungers is masked 80 completely. In the joint application above referred to, this structure is very fully described and claimed.

The leveling roll 20 itself is mounted in 85 a carriage 110 having arc or segment-shaped lateral extremities at 112 whereby it may be rotated about a vertical axis in the head 18 and held in adjustable position by a screw and slot arrangement at 114. This enables the roll to be adjusted to suit certain kinds and conditions of work. A pad 116 rests upon the top of the roll to wipe off dirt. A gage 118 is mounted in the head 110 to extend outwardly over the front of the roll and serve as a guide for 95 the jacking of the toe tip of the shoe so that it may be placed at the proper height prior to the beginning of the leveling operation.

The toe post 58 has at its upper end a 100 socket 120 arranged to hold a toe rest 122 provided for purposes of the present invention. This toe rest is made of resilient material of such thickness as to permit a very substantial deformation under ordinary leveling pressure. By this is meant that it can be readily deformed by amounts such as $\frac{1}{2}$ or $\frac{3}{4}$ inch under this pressure substantially equal, for example, to 25 per cent of the height and width dimensions of 105 the toe of a shoe. I have found soft rubber to be excellently adapted for the purposes of this rest.

This rubber in the form shown in Fig. 2, 110 is substantially flat on top, not being hollowed out in any effort to fit the toe of the shoe. The ordinary jacking pressure exerted through the mechanism at 124 which is well known and need not be further described here, will cause the toe to sink 115 appreciably into the rubber before the leveling operation begins, as shown at 126.

Figs. 3 and 4 show two modified forms of 120 rubber block which have certain advantages. The block shown in Fig. 3 has a slight depression 128 to serve as a gage for the longitudinal positioning of the shoe in the jacking operation. It is not contemplated that this depression shall necessarily 125 fit the toe; it simply serves as a mark that 130

the operator can see. Fig. 4 shows a rubber block with a raised rib 130 for the same purpose.

In order to understand the advantages of this invention it is necessary to consider the nature of the pressures and reactions in the leveling machine. The trunnions at 14 are horizontal, so that the leveling arms 12 can move only in a vertical plane. The axis 10 at 62, on which the jacks rock, is parallel to the axis at 14, so that the relative movement of the shoe and leveling roll in a direction lengthwise of the shoe is also in the same vertical plane. With the parts in 15 this relation and with the leveling roll inclined to the horizontal as it frequently is in operating along the margin of the sole at the side of a shoe, the pressure of the roll tends to swing the shoe laterally about the 20 heel pin, and this tendency is considerably increased as the roll encounters the wider and higher portions of the sole, as in passing from the shank to the ball of the shoe, and is thus forced to swing upwardly. If 25 it were not for provision for substantial relative movement of the roll and the shoe laterally of the shoe at such times, the roll by its upward movement in a direction inclined to its axis would rub on the margin 30 of the sole with danger of objectionable results such as hereinbefore set forth. The soft rubber cushion or toe rest 122, however, yields with the shoe. In response to the pressure of the roll, to such an extent 35 as to counteract the tendency of the inclined roll to rub on the sole. In other words, the result of the lateral yield of the shoe and the vertical yield of the roll is, in effect, a relative yield substantially perpendicular to the surface on which the inclined roll is operating, so that the roll has simply a rolling action without substantial rubbing action. Moreover, where the 40 contour of the shoe results in a downward movement of the roll, the resilient toe rest acts to effect a return movement of the shoe laterally as permitted by the lessened resistance of the roll, and thereby counteracts the tendency of the roll to rub on the 45 sole at that time also, while assisting in maintaining proper leveling pressure on the margin of the sole. Similarly, when the roll tips from one side of the shoe to the other, the shoe is automatically centralized, 50 so that it is presented in proper relation for the roll to begin its operation on the opposite side of the sole. An important factor in these desirable results is the fact that the soft rubber toe rest clings to the 55 surface of the upper so that the shoe as it yields carries the top of the resilient toe rest with it, and a further very important advantage in this is that no rubbing takes place between the shoe and the toe rest, so 60

that danger of damage to the surface of the 65 upper is avoided.

There is still another important advantage in the use of a toe supporting cushion or rest such as herein described.

According to the former practice, as hereinbefore explained, it has been the custom to provide toe rests which were shaped, as well as might be, to the shape of the toe of the shoe, for the purpose, among others, of supporting the shoe against the lateral 75 pressure, and avoiding the scratching and rubbing consequent on any yielding to such pressure. It being practically impossible to provide and use a toe rest exactly fitted to each shoe, this only partially met the rubbing difficulty, and moreover, when small toes were put into rests too large for them, the shoe had a tendency to settle down and back into the rest so far that the rest instead of the shoe took the pressure of the roll as 80 it tipped around the toe. Inasmuch as a tipping of the roll around on the toe end of the sole is necessary in order to shape the shoe properly at this point, the machine failed to do good work in this regard under 85 the described circumstances. With the machine of the present invention all shoes are jacked to the same height on the soft rubber toe rest and proper and uniform treatment 90 of all shoes results.

Having described my invention, what I claim as new and desire to secure by Letters Patent of the United States is:—

1. In a leveling machine, the combination with a leveling tool arranged to apply pressure to the margin of the bottom of a shoe in a direction inclined to the height of the shoe and to act progressively on different portions of said margin along the side of the shoe, of means for relatively positioning the shoe and the tool constructed and arranged to provide for relative movement of the shoe and the tool laterally of the shoe in different directions successively in accordance with variations in the contour of the shoe in the progressive action of the tool along the side of the shoe.

2. In a leveling machine, a leveling tool arranged to apply pressure to the margin of the bottom of a shoe in a direction inclined to the height of the shoe and to act progressively on different portions of said margin along the side of the shoe, controlling means for the shoe to position it relatively to the tool, and controlling means for the tool to press it upon the shoe, said controlling means being constructed and organized to effect relative movement of the shoe and the tool laterally of the shoe in different directions successively in accordance with variations in the contour of the shoe in the progressive action of the tool along the side of the shoe.

3. In a leveling machine, the combination with a leveling roll arranged to act along the margin of the bottom of a shoe with its axis inclined to the height of the shoe, and controlling means affording provision for relative movement of the roll and the shoe heightwise of the shoe in directions inclined to the axis of the roll, of additional controlling means constructed and arranged to provide for relative movement of the shoe and the roll laterally of the shoe in opposite directions to counteract the tendency for the roll to rub on the shoe in the relative movements of the shoe and the roll heightwise of the shoe. 65
4. In a leveling machine, the combination with a leveling tool arranged to apply pressure to the margin of the bottom of a shoe in a direction inclined to the height of the shoe and to act progressively on different portions of said margin along the side of the shoe, of means for relatively positioning the shoe and the tool constructed and arranged to provide for relative movement of the shoe and the tool laterally of the shoe in response to resistance to the leveling pressure and to effect relative return movement of the shoe and the tool in accordance with variations in the contour of the shoe in the progressive action of the tool along the side of the shoe. 80
5. In a leveling machine, a leveling tool arranged to apply pressure to the margin of the bottom of a shoe in a direction inclined to the height of the shoe and to act progressively on different portions of said margin along the side of the shoe, a support for said leveling tool, and a support for the shoe, one of said supports being yieldable in a direction heightwise of the shoe, and the other support being yieldable laterally of the shoe in accordance with variations in the contour of the shoe in the progressive action to the tool along the side of the shoe. 85
6. In a leveling machine, the combination with a leveling tool arranged to apply pressure to the margin of the sole of a shoe in a direction inclined to the height of the shoe and to act progressively on different portions of the margin of the sole along the side of the shoe, of resilient means for relatively positioning the shoe and the tool constructed and arranged to provide for relative movement of the shoe and the tool laterally of the shoe as the tool encounters the wider portions of the sole and to effect a relative return movement thereof as narrower portions of the sole are presented to the tool. 100
7. In a leveling machine, the combination with a leveling tool arranged to apply pressure to the margin of the sole of a shoe in a direction inclined to the height of the shoe and to act progressively on different portions of the margin of the sole along the side of the shoe, of means for relatively displacing the shoe and the tool laterally of the shoe when the tool encounters the wider portions of the sole, and resilient means for effecting relative return movement of the shoe and the tool as narrower portions of the sole are presented to the tool. 115
8. In a leveling machine, the combination with a leveling tool arranged to apply pressure to the margin of the sole of a shoe in a direction inclined to the height of the shoe and to act progressively on different portions of the margin of the sole along the side of the shoe, of a device for relatively positioning the shoe and the tool comprising resilient means affording provision for substantial relative yield of the shoe and the tool laterally of the shoe in response to the leveling pressure and tending to effect relative return movement of the shoe and the tool laterally of the shoe to maintain constantly proper leveling pressure on the shoe. 120
9. In a leveling machine, the combination with a leveling tool arranged to apply pressure to the margin of the sole of a shoe in a direction inclined to the height of the shoe and to act progressively on different portions of the margin of the sole along the side of the shoe, of means for positioning the shoe constructed and arranged to provide for lateral movement of the shoe relatively to the tool and to effect return movement of the shoe relatively to the tool. 125
10. In a leveling machine having shoe supporting means and a leveling tool arranged to apply pressure to the margin of the bottom of the shoe in a direction inclined to the height of the shoe, mechanism for relatively positioning the shoe and the tool comprising resilient means constructed and arranged to permit substantial relative yield between the shoe and tool in a direction inclined to the height of the shoe and substantially normal to that portion of the surface of the shoe upon which the tool is operating. 130
11. In a leveling machine having shoe supporting means and a leveling tool arranged to apply pressure to the margin of the bottom of the shoe in a direction inclined to the height of the shoe, the combination with controlling means arranged to permit the tool to yield heightwise of the shoe only in response to variations in the contour of the shoe bottom, of additional controlling means comprising a resilient device affording provision for substantial yield of the shoe laterally in the operation of the tool on the shoe. 135
12. In a leveling machine, the combination with a leveling roll arranged to operate along the margin of the bottom of a shoe with its axis inclined to the height of the shoe, of a shoe support comprising a resilient toe rest yieldable laterally of the shoe in

response to the pressure of the roll and tending constantly to return the shoe to a central position.

13. In a leveling machine, the combination with a leveling roll arranged to operate along the margin of the sole of a shoe with its axis inclined to the height of the shoe, and resilient means permitting the roll to yield heightwise of the shoe in response to variations in the contour of the shoe, of a shoe supporting toe rest comprising resilient means arranged to permit substantial lateral swinging movement of the shoe about an axis at its heel end under the pressure of the roll and acting to return the shoe to a central position when permitted by the roll.
14. In a leveling machine, a shoe supporting jack, a leveling arm carrying a tool and pivoted to move normally in a plane extending heightwise of the shoe, means for relatively oscillating the arm and jack in said plane, and means for effecting relative tipping movements between the tool and the shoe about an axis generally parallel to the longitudinal axis of the shoe as the tool passes over the shoe, said jack comprising a device contacting with and supporting the toe of the shoe and resiliently permitting substantial lateral displacement of the shoe under lateral stress without relative movement between the shoe and the shoe engaging surface of said device during the leveling operation.

15. In a leveling machine, a shoe supporting jack, a leveling arm carrying a tool and pivoted to move normally in a plane extending heightwise of the shoe, means for relatively oscillating the arm and jack in said plane, and means for effecting relative tipping movements between the tool and the shoe about an axis generally parallel to the longitudinal axis of the shoe as the tool passes over the shoe, said jack comprising a soft rubber toe rest of substantial thickness for resiliently supporting the toe of the shoe and permitting it to yield under lateral stress while clinging to the surface of the upper and for restoring the shoe to normal position when the lateral stress is relieved.

16. In a leveling machine, a shoe holding means comprising a heel post, and a toe post having a toe rest formed of a substance so resilient as to be distorted heightwise and widthwise to an extent amounting respectively to substantially 25% of the height and width dimensions of the toe of a shoe under the stresses of the leveling operation.
17. In a leveling machine, a shoe holding jack, and a leveling tool arranged for move-

ment generally perpendicular to the sole of a shoe on the jack, the jack being provided with a toe rest for the shoe formed of soft rubber of such thickness as to permit a substantial yielding of the shoe when the pressure of the leveling tool is applied to the shoe and acting when deformed to force the shoe toward the leveling tool.

18. In a leveling machine, a shoe holding jack, a leveling arm arranged for pivotal movement in a single plane generally perpendicular to the sole of a shoe on the jack, means for relatively oscillating the arm and jack, and a soft rubber toe rest on the jack arranged to support the toe of the shoe and to yield heightwise and widthwise to an extent amounting respectively to substantially 25% of the height and width dimensions of the toe of the shoe when the leveling arm is transferring its pressure up the shank of a shoe toward the ball.

19. In a leveling machine, shoe-positioning means comprising a toe-supporting cushion of soft rubber of such thickness as to yield substantially under leveling pressure directed laterally of the shoe and adapted to cling to the upper of the shoe during said yield to avoid scarring the upper.

20. In a leveling machine, a shoe holding means comprising a toe rest formed of resilient material and constructed to yield substantially under pressure directed laterally of the shoe and to cling to the contacting portion of the shoe upper during said yield, whereby scarring the upper is avoided and the shoe is returned to normal position when the pressure is removed, in combination with a leveling roll and means for tipping it around on the end of the shoe toe during the leveling operation.

21. In a leveling machine, a shoe holding jack, a leveling arm carrying a roll, means for relatively oscillating the arm and the jack, means for tipping the roll as it passes over the shoe to adapt its position to the contour of the sole of a shoe on the jack, and a soft rubber toe rest on the jack arranged to support the toe of the shoe and of such thickness as to yield substantially in directions laterally of the shoe in response to pressure of the inclined roll on the shoe.

22. A toe rest for a leveling machine having a generally flat upper surface but having also portions of elevation different from that of the remainder to serve as a gage in jacking a shoe.

In testimony whereof I have signed my name to this specification.

HERMAN A. DAVENPORT.

CERTIFICATE OF CORRECTION.

Patent No. 1,602,393.

Granted October 12, 1926, to

HERMAN A. DAVENPORT.

It is hereby certified that error appears in the printed specification of the above numbered patent requiring correction as follows: Page 3, line 85, for the misspelled word "cariage" read "carriage"; line 114, after the word "rubber" insert the word and comma "block, "; page 4, line 33, after the word "shoe" strike out the period and insert a comma, and for the word "In" read "in"; page 6, line 68, claim 17, for the word "too" read "tool"; line 71, claim 13, for the misspelled word "generaly" read "generally"; and that the said Letters Patent should be read with these corrections therein that the same may conform to the record of the case in the Patent Office.

Signed and sealed this 28th day of June, A. D. 1927.

Seal.

M. J. MOORE.
Acting Commissioner of Patents.
